UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,276,360.

Specification of Letters Patent. Patented Aug. 20, 1918.

Original application filed June 19, 1916, Serial No. 104,449. Divided and this application filed March 19, 1917. Serial No. 155,848.

To all whom it may concern:

Be it known that I, GEORGE S. HILL, a citizen of the United States, residing at Strafford, in the county of Strafford and 5 State of New Hampshire, have invented certain new and useful Improvements in Sewing-Machines; and I do hereby declare the following to be a full, clear, and exact description of the invention, such as will enable others skilled in the art to which it 10 pertains to make and use the same.

The invention relates to machines for sewing overseams, and more particularly to machines adapted for sewing buttonholes.

15 The present application is a division of application Serial No. 104,449, filed June 19, 1916.

20 The object of the invention is to provide novel and improved needle jogging mechanism which will run smoothly and without strain or wear on the parts when operated at high speed. To this end the upper needle bar reciprocates in a carrier which is also vertically reciprocated at half the speed of 25 the needle bar, and is so connected with its supports that the vertical reciprocation causes the carrier to vibrate laterally. The carrier is preferably connected with a relatively fixed support by a link which swings 30 about its fixed pivot as the carrier moves vertically, thus moving the carrier toward and from the fixed pivot.

35 The various features of the invention will be readily understood from an inspection of the accompanying drawings and the following detailed description of the machine shown therein.

40 In the drawings, Figure 1 is a sectional elevation showing so much of a buttonhole making machine as is necessary to illustrate the application of the present invention thereto; Fig. 2 is a sectional front elevation showing the needle jogging mechanism; Fig. 3 is a detail sectional view on an enlarged 45 scale, showing a part of the needle jogging mechanism; Fig. 4 is a sectional plan view on line 4, Fig. 3; and Fig. 5 is a sectional view through the hub of the gear which rotates the upper needle mechanism, taken on 50 the broken line 5 of Fig. 4.

In the drawings the invention is shown embodied in a machine for making button-

holes in which the overseam stitches extend along the sides and about the eyed end of the buttonhole, the buttonhole slit being cut after the completion of the sewing. The machine 55 comprises in general a cutter, a reciprocating and laterally moving work clamp, and a sewing mechanism which is rotated during the sewing about the eye of the buttonhole, and which comprises a vertically reciprocating and laterally vibrating or jogging upper 60 needle and two alternately acting loopers and loop spreaders, one of the loopers carrying an under thread.

65 As shown, the upper needle 2 is secured in the lower end of a hollow needle bar 4 which is mounted to reciprocate within a laterally vibrating carrier sleeve 6. The needle bar is reciprocated by a crank 8 secured on the 70 forward end of the needle shaft 10, the rear end of which carries a beveled pinion 12 engaged and driven by a beveled gear 14 of twice its diameter secured to the sewing shaft 16. The crank is connected to the 75 needle bar by a link 18, the opposite ends of which engage ball joints on the crank and upper end of the needle bar. The means for laterally vibrating the carrier sleeve comprises a link 20, one end of which is connected to the lower end of the sleeve, and the other end of which is mounted on a stud 22 secured in a rotary head 24. The upper end of the sleeve is connected to the horizontal 80 arm of a bell crank rock lever 26 by a ball joint. The vertical arm of the bell crank lever is connected to the forward end of a rod 28 by a pivot block 30 which is adjustably secured on the arm by a bolt passing 85 through a slot in the arm. The rear end of the rod 28 is provided with an eccentric strap 32 engaging an eccentric 34 on the sewing shaft 16. When the carrier sleeve is moved downward from the position indicated in Fig. 3, the link 20 will act to swing the lower end of the carrier and the needle bar toward the right, so that the needle will 90 be in position to form the depth stitch of the overseam. When the carrier sleeve is raised, the link will act to swing the sleeve 95 toward the left into the position indicated in Fig. 3, thus bringing the needle into position to form the slit or edge stitch of the overedge seam. Since the needle shaft 10

2

makes two revolutions for each revolution of the sewing shaft 16, the eccentric on the shaft 16 will move the needle carrier to the right during one reciprocation of the needle, 5 and to the left during the succeeding reciprocation, so that the needle will be laterally vibrated or jogged during the sewing to alternately form the depth and edge or slit stitches. That part of the stud 22 which is 10 engaged by the link 20 is eccentric to the parts of the stud which engage the head 24, so that the point at which the needle penetrates the work in making the slit stroke may be accurately adjusted by turning the stud 15 and then securing it in adjusted position. The amplitude of the vibrations of the needle, and consequently the distance between the depth and edge stitches, may be varied by adjusting the pivot block 30 in the arm of the bell crank lever 26.

20 The lower end of the needle carrier sleeve 6 is rectangular in shape, and fits within a guide slot 36 formed in the head 24. The key block 38 is secured to one side of the carrier sleeve forming a continuation of the rectangular lower end of the sleeve, and also fits within the guide slot 36. The key block is provided with a key 40 which projects through a longitudinal slot in the carrier sleeve, and into a keyway 42 in the needle bar, thus holding the needle bar against rotation within the sleeve, and also connecting it with the sleeve and head 24, so that the sleeve, head and bar will rotate 25 in unison when rotary motion is imparted to the head. The head is secured to the lower end of the hub 44 of a bevel gear 46 by screws 48, the head being held against rotation with relation to the gear hub by lugs 50 30 which enter recesses 52 in the lower end of the hub. The bevel gear is mounted in a bearing in the machine frame, and is connected through a gear 54 to a shaft 56 through which the upper needle mechanism 35 is rotated during the sewing about the eye of the buttonhole.

40 The shaft 56 is operated to rotate the upper needle mechanism through a lever 58 provided at its end with a gear segment 58 engaging a gear 60 on the end of the shaft. The segment lever is connected by a link 62 45 with a similar segment lever 64 which is provided with an arm 66 carrying a roll engaging a cam groove 68 formed in the face of a gear 70 secured to the cam shaft 72. The gear segment on the end of the lever 64 55 engages a gear 74 on the rear end of a shaft 76, the front end of which carries a gear 78 60 engaging a similar gear 80 secured to the lower end of the rotary turret 82 on which the loopers and loop spreaders of the sewing mechanism are carried. The turret is provided with upper and lower cylindrical bearing 65 surfaces engaging corresponding bearing surfaces in the turret bracket 84, and

is rotated in unison with the head which carries the upper needle mechanism during the sewing about the eye of the buttonhole, and is rotated in the opposite direction after the completion of the buttonhole to bring 70 the sewing mechanism into initial position through the connections described.

In the machine shown, the work clamps, indicated at 86, are mounted upon work supporting plates 88 which are pivoted on a 75 longitudinally and laterally moving clamp carriage 90. The clamps are automatically closed before the beginning of the sewing, and are automatically opened after the completion of a buttonhole by mechanism which 80 forms no part of the present invention, and which need not be described. The buttonhole slit is cut after the completion of the sewing by a cutter 92 operated by a cam on the main cam shaft 72 of the machine. The 85 work is carried by the clamp over the throat plate 94 which is mounted upon the turret 82.

While the invention has been shown and described as embodied in a machine for sewing an overseam about the edge of a buttonhole, it will be understood that certain features of the invention are not limited in their application to a machine of this type, and it will also be understood that the invention is not limited to the specific construction and arrangement of parts shown and described, but may be embodied in other machines, or in other constructions, and that the specific construction and arrangement of parts may be varied or modified as found desirable or best suited to the machine or mechanism in which the invention is to be embodied.

Having explained the nature and object of the invention, and specifically described one form of mechanism in which it may be embodied, what is claimed is:—

1. A sewing machine, having, in combination, a vertically reciprocating needle bar, a vertically reciprocating carrier in which the needle bar reciprocates, and connections through which the vertical movement of the carrier causes it to move laterally.

2. A sewing machine, having, in combination, a vertically reciprocating needle bar, a vertically reciprocating carrier in which the bar reciprocates, connections through which the vertical movement of the carrier causes it to move laterally, and mechanism 110 for reciprocating the carrier at half the speed of the needle bar.

3. A sewing machine, having, in combination, a vertically reciprocating needle bar, a vertically reciprocating carrier in which the bar reciprocates, and a link connected 115 to the carrier to move it laterally.

4. A sewing machine, having, in combination, a vertically reciprocating needle bar, a vertically reciprocating carrier in which 120

the bar reciprocates, a link connected to the carrier to move it laterally, and means for adjusting the working position of the carrier laterally.

5 5. A sewing machine, having, in combination, a vertically reciprocating needle bar, a vertically reciprocating carrier in which the bar reciprocates, a link connected to the carrier, and a vertically oscillating arm connected to the upper end of the carrier.

10 6. A sewing machine, having, in combination, a vertically reciprocating needle bar, a carrier in which the bar reciprocates, a crank and connections for reciprocating the bar, an eccentric and connection for vertically reciprocating the carrier, and connections through which the vertical movement of the carrier causes it to move laterally.

20 7. A sewing machine, having, in combination, a vertically reciprocating needle bar, a carrier sleeve surrounding the bar, a link connected to the lower end of the sleeve, and a reciprocating arm connected to the upper end of the sleeve by a universal joint.

25 8. A sewing machine, having, in combination, a vertically reciprocating needle bar, a vertically reciprocating carrier in which the bar reciprocates, a crank for reciprocating the needle bar, a lever connected by a ball joint to the upper end of the carrier, an eccentric for reciprocating the lever, and a link connecting the carrier to a relatively stationary support.

30 9. A sewing machine, having, in combination, a vertically reciprocating needle bar, a carrier sleeve within which the bar reciprocates, a rotary head, a link connecting the sleeve and head, and mechanism for vertically reciprocating the sleeve.

35 10. A sewing machine, having, in combination, a vertically reciprocating needle bar, a carrier sleeve within which the bar reciprocates, a rotary head provided with a transverse slot for the lower end of the sleeve, a key and keyway connecting the sleeve and needle bar, mechanism for vertically recip-

rocating the sleeve, and connections between the head and sleeve for causing the sleeve 50 to move laterally.

11. A sewing machine, having, in combination, a vertically reciprocating needle bar, a carrier sleeve within which the bar reciprocates, a rotary head, a link connecting the lower end of the sleeve with the head, a lever having a horizontal arm connected with the upper end of the sleeve by a universal joint, and an eccentric and connections for reciprocating the lever. 60

12. A sewing machine, having, in combination, a vertically reciprocating needle bar, a carrier sleeve within which the bar reciprocates, a link connecting the sleeve to a relatively fixed support, said support, an adjustable pivot for one end of the link, and mechanism for reciprocating the carrier sleeve. 65

13. A sewing machine, having, in combination, a vertically reciprocating needle bar, a crank for reciprocating the bar, a link connecting the crank and bar, a carrier sleeve within which the bar reciprocates, a lever connected to the sleeve, an eccentric connected to reciprocate the lever, a link connecting the sleeve to a fixed support, and said support. 70 75

14. A sewing machine, having, in combination, a vertically reciprocating needle bar, a vertically reciprocating carrier within which the bar reciprocates, connections through which the vertical movement of the carrier causes it to move laterally, and connections for varying the vertical travel of the carrier. 80 85

15. A sewing machine, having, in combination, a vertically reciprocating needle bar, a vertically reciprocating carrier within which the bar reciprocates, connections through which the vertical movement of the carrier causes it to move laterally, a lever connected to the upper end of the carrier, and connections through which the lever is oscillated adjustably connected with the lever to vary its throw. 90
